DESIGN FOR A MARKING DEVICE FOR WINDOW SCREENS, STORM WINDOWS, OR THE LIKE

John E. Gaulke, Milwaukee, Wis.

Application January 19, 1948, Serial No. 143,883

Term of patent 7 years

(Cl. D64—10)

To all whom it may concern:

Be it known that I, John E. Gaulke, a citizen of the United States, residing at Milwaukee, in the county of Milwaukee, and State of Wisconsin, have invented a new, original, and ornamental Design for a Marking Device for Window Screens, Storm Windows, or the like, of which the following is a description, reference being had to the accompanying drawing, forming a part thereof.

In the drawing:

Fig. 1 is a front and side perspective view showing my new marking device;

Fig. 2 is a top view of the marking device; and

Fig. 3 is a front view thereof.

I claim:

The ornamental design for a marking device for window screens, storm windows, or the like, substantially as shown.

JOHN E. GAULKE.
